UNITED STATES PATENT OFFICE

LEWIS M. HULL, OF MOUNTAIN LAKES, NEW JERSEY, ASSIGNOR TO RADIO FREQUENCY LABORATORIES, INCORPORATED, OF BOONTON, NEW JERSEY, A CORPORATION OF NEW JERSEY

ELECTRICAL AMPLIFIER CIRCUIT

Application filed December 15, 1928. Serial No. 326,345.

This invention relates to electrical amplifier circuits of the type employing electron or vacuum tubes including an emitting cathode, an anode or plate, and one or more additional elements usually having the form of grids, one of which ordinarily serves as the control element. Such tubes are now commonly known as "audions", "triodes", "tetrodes", and so forth. The invention relates especially to a balanced amplifier circuit of the foregoing type, and provides means for reducing, eliminating, or controlling retroaction or regeneration from the output circuit of such an amplifier stage to the input circuit thereof. This retroaction or regeneration may be caused by coupling due to capacities existing between the elements of the tube and the connections associated therewith, and especially by coupling due to capacity between the anode or plate and control element or grid of the tube. The invention relates also to a balanced amplifier circuit of the foregoing type in which such retroaction or regeneration may be controlled by means of a deliberate partial unbalance of the circuit, and particularly to such a circuit in which the amount or degree of such unbalance may increase with increasing wavelength at a predetermined rate over a part or all of a given range of wavelength.

Referring now to the drawings Figure 1 shows a portion of a multistage electrical amplifier including audions of the three-electrode type and arranged according to one embodiment of my invention. Figure 2 shows a similar amplifier circuit arranged according to another embodiment of my invention. Figures 3a, 3b, 3c and 3d are curves illustrative of the operation of the circuit shown in Figure 1. Figure 4 shows similar curves illustrative of the circuit shown in Figure 2.

In the arrangement shown in Figure 1, T_1 is a three-element audion tube provided with a plate P , a grid G , and a filament F . The latter may suitably be of direct current, A. C., or heater type, and is here shown as an A. C. filament supplied with heating current from a houselighting source of alternating current through a suitable transformer. A shunt

resistance R may be connected across the filament, each side of which may also be bypassed to ground by means of by-pass condensers C' as shown, in the well-known manner. A grid-biasing resistance R' may also be connected between a suitable point in the filament system and ground, as shown. The input circuit for the amplifier stage including the tube T_1 may assume any desired form, and is here shown as including the tuned circuit L_2-C_2 , of which L_2 constitutes the secondary of an input transformer L_1-L_2 . As representative of the impedance of a preceding amplifier stage, as is the case in a multistage arrangement, is shown the resistance R_0 , equal to say 10,000 ohms, connected in series with the input transformer primary. The plate coil of tube T_1 , or output transformer primary, L_1 , is connected between the anode P and the cathode F , preferably in series with a suitable "B"-battery or other source of plate potential, which may be bypassed in a well-known manner by the condenser C' . Coupled to the output transformer primary L_1 with mutual inductance M_{12} is the output transformer secondary L_2 . These primary and secondary coils have negative coupling, that is, one coil is wound or connected in reverse sense as regards the other, so that if an alternating current is assumed to flow through the series resonant circuit of which L_2 forms a part, the voltage drop across L_2 due to this current will be substantially opposite in phase to the voltage drop across the primary coil L_1 induced therein through the mutual inductance M_{12} by the current flowing in L_2 . While it is possible to employ substantially unity coupling between the coils L_1 and L_2 , it is ordinarily not necessary to do so, and I usually prefer to employ less than unity coupling between them, thereby avoiding the high losses which are apt to take place in physical constructions employing unity coupling between reversed transformer coils. In series with the secondary L_2 is connected a composite impedance including a balance coil L_3 and an unbalancing capacity C'_3 . The coil L_3 and capacity C'_3 which constitute this composite impedance may be arranged either in

series, as shown in Figure 1, or in parallel as shown in Figure 2, as will be hereafter described, and the capacity C'_3 may be constituted either by a separate condenser or, wholly or in part, by distributive capacity of coil L_3 . The secondary L_2 is tuned by tuning condenser C_2 , which is connected across both the secondary L_2 and the composite impedance $L_3-C'_3$ in series. The balance coil L_3 is preferably substantially uncoupled with either the coil L_1 or the coil L_2 , and the coupling between the balance coil and both the primary and the secondary is in any case negligible. I find that such coupling is obtained, for all practical purposes, when the mutual inductance between the balance coil and the secondary is negligible in comparison with the self-inductance of these coils. Such negligible coupling may be provided by the use of an electrical transformer in which the coil L_3 is mounted at right angles to the primary and secondary coils, as is described and claimed in the copending application of Frederick H. Drake and William D. Loughlin, Serial No. 275,449, filed May 5, 1928. A balance condenser C_2 may be connected between the grid G and point X between the coils L_2 and L_3 , although in certain cases the natural capacities of the circuit, between the elements thereof, may serve as the partial or complete equivalent of the capacity C_2 . Since the cathode F is grounded, as is the low potential side of the tuning condenser C_2 at its junction with the composite impedance $L_3-C'_3$, a connection exists between these points. This is of advantage for example in multistage amplifiers employing a ganged tuning condenser, and in other cases.

An approximate balance condition for the circuit illustrated in Figure 1 may be expressed as follows:

$$\frac{C_3}{C_m} = \frac{\omega M_{12}}{\omega L_3 - \frac{1}{\omega C'_3}} \quad (1)$$

when

$$\omega^2 L_3 C'_3 > 1 \quad (2)$$

where C_m is equal to the total effective grid-plate capacity of the tube T_1 , ω = the angular velocity of the current, and the other symbols designate the magnitude of the corresponding elements as indicated in the drawing.

As one specific illustration of certain constants which I have found to produce satisfactory operation in the circuit of Figure 1, I may mention the following:

Tube	= UX 226
E_f	= 1.5 volts
E_o (grid bias)	= -6 volts
E_B	= 90 volts
L_1	= $\begin{cases} (a) 20 \text{ turns } \#36 \text{ enamel copper wire on } 1" \text{ form, } 1" \text{ winding space} \\ (b) 20 \text{ turns } \#35 \text{ nichrome wire on } 1" \text{ form, } 1" \text{ winding space.} \end{cases}$
L_2	= 87 turns $\#30$ enamel copper wire on $1\frac{1}{2}"$ form
L_3	= 50 turns $\#30$ enamel copper wire on $1\frac{1}{2}"$ form
C'_3	= .002 m. f.

For the circuit balanced at a wavelength

of 200 meters by means of balance capacity C_3 , Figures 3a and 3b show sample curves obtained by plotting the gain per stage E/E_0 , where E is the voltage across the output tuning condenser and E_0 the voltage across the input tuning condenser, against wavelength in meters, for different values in microfarads of the capacity C'_3 , and for the copper-wire and resistance primaries, respectively, and other circuit constants noted above. In this as well as other modifications of the present invention, the unbalance may be controlled and the shape of the gain characteristic altered, by means of the relative magnitudes of the elements causing secondary unbalance, i. e. composite impedance $L_3-C'_3$, balance capacity C_3 , and so forth, or by means of the resistance in the primary circuit including L_1 .

With regard to these curves it will be noted that the curve marked $C'_3 = \infty$ indicates the operation of the circuit when the condenser C'_3 is omitted from the composite impedance $L_3-C'_3$, while the other curves show the improved operation and amplification of the circuit for different values of C'_3 . The curve marked $C'_3 = .002$ m. f., for a resistance primary shows, for example, a high gain characteristic for an amplifier stage.

Figure 3c shows the various amounts of balance capacity C_3 required to produce an aural balance at a wavelength of 200 meters for various values of the capacity C'_3 in the composite impedance. Figure 3d shows the balance capacity C_3 required to produce an aural balance at various wavelengths for $C'_3 = .005$ m. f. Taken together, these curves show the progressive unbalance of this circuit obtained under the conditions indicated.

Figure 2 illustrates a portion of a multi-stage electrical amplifier circuit which is similar to that shown in Figure 1, except that in this arrangement the composite impedance $L_3-C'_3$ is arranged as a parallel instead of a series circuit. The other connections correspond with those shown in Figure 1, although a portion of a preceding stage is here illustrated as including the tube T , rather than merely the equivalent resistance R_o .

As an example illustrative of suitable constants for a circuit arrangement such as that of Figure 2, I may mention the following:

Tube	= UX 226
E_f	= 1.5 volts
E_o	= -6.0 volts
E_B	= 90 volts
L_1	= $\begin{cases} (a) 20 \text{ turns } \#36 \text{ enamel copper wire on } 1" \text{ form, } 1" \text{ winding space} \\ (b) 20 \text{ turns } \#35 \text{ nichrome wire on } 1" \text{ form, } 1" \text{ winding space} \end{cases}$
L_2	= 87 turns $\#30$ enamel copper wire on $1\frac{1}{2}"$ form
L_3	= 50 turns $\#30$ enamel copper wire on $1\frac{1}{2}"$ form
C'_3	= .00025 μ f.
L_4	= approximately 30μ h.

The composite impedance $L_3-C'_3$ is then resonant at a wavelength near 200 meters.

When the circuit is balanced at a wave-

length of 200 meters, typical gain characteristics are indicated by the curves in Figure 4, which are, respectively, for a copper wire primary and a resistance wire primary. Variations of these gain characteristics can, of course, be produced as explained above, either by adjusting the secondary unbalance of the network or by varying the resistance in the primary circuit.

An approximate theoretical balance condition for the circuit shown in Figure 2 may be expressed as follows:

$$\frac{C_3}{C_m} = \frac{M_{12}}{L_3} (1 - \omega^2 L_3 C'_3) \quad (3)$$

when

$$\omega^2 L_3 C'_3 < 1 \quad (4)$$

over the frequency range for which the circuit is intended to operate, and where the symbols have the meanings indicated in connection with equations 1 and 2 above.

The application of the present invention is not limited to audion tubes of the three-element type, and it may be applied, when desired, to tubes of the so-called double-grid or shield-grid, or other, type. In such case the control grid of the tube is ordinarily connected as is the grid G in Figures 1 and 2, although suitable modifications of the circuit may of course be made.

The present invention constitutes an improvement upon the invention described and claimed in U. S. Patent No. 1,672,811, and also, in the cases where resistance primaries are employed, may constitute an improvement upon the invention described and claimed in the copending application of Frederick H. Drake and Paul O. Farnham, Serial No. 275,189, filed May 4, 1928.

In electrical amplifier circuits of the balanced type the amplification or gain is apt to be higher at short wavelengths than at longer wavelengths. For many purposes it is desirable, however, to make the amplification or gain in the stage at the longer wavelengths on which the amplifier may be called upon to operate, higher than it would ordinarily be, and often at least as high as the gain at the shorter wavelengths of the wavelength range of the amplifier. Through the use of the present invention, as will have appeared from the foregoing description, the amplification is increased at the longer wavelengths of the wavelength range of the amplifier by proportioning the elements of the network so as to give a controlled secondary unbalance conducive to regeneration, and this regenerative unbalance may suitably be arranged to increase with increasing wavelengths. This increase may also be made at a predetermined rate by proper proportioning of the circuit constants in accord with the explanations given above.

The specific circuit arrangements and ex-

amples of circuit constants given herein are only illustrative of my invention, which is not limited thereto, but which includes many variations and modifications thereof.

I claim:

1. An electrical amplifier stage comprising, in combination, a vacuum tube including at least an anode, a cathode, and a control grid; an input circuit for said stage connected to said control grid; an output coupling coil connected between said anode and said cathode; a tuned circuit including in series a second coil coupled in reverse sense to said output coil, a tuning condenser, and a composite impedance including a capacity and a third coil having negligible electromagnetic coupling with said second coil; and a balancing condenser connected between said control grid and the junction of said second coil and said composite impedance, the inductance and capacity of said composite impedance being so related that conditions for reactive balance are variant with frequency, whereby adjustment of the stage to provide a substantial reactive balance at one frequency results in a reactive unbalance at other frequencies within the range of adjustment of said tuned circuit.

2. An electrical amplifier stage including a vacuum tube having at least an anode, a cathode, and a control grid; an input circuit associated with said control grid; a tuned output circuit including a tuning condenser having one terminal connected to said cathode, and two coils having negligible electromagnetic coupling with each other, one of said coils being coupled to a coil connected between said anode and cathode, and the other of said coils being associated with a capacity to form a composite impedance; and a capacitive impedance connected between said control grid and one of said coils, whereby said stage may be balanced to reduce retroactive effects due to capacitive coupling between said output and input circuits, the capacity of said composite impedance being of a magnitude to render the reactive balance of said stage variant with frequency.

3. An electrical circuit comprising, in combination, an electron tube including at least an anode, a cathode, and a control means; an input circuit associated with said control means; a coil associated with said anode and cathode; a second coil coupled to said first coil in the reverse sense; a composite impedance including a capacity and a third coil having negligible electromagnetic coupling with said second coil, said composite impedance having one terminal connected to said second coil; a tuning condenser connected between the non-common terminals of said second coil and said composite impedance, a balancing circuit including capacitive impedance, said balancing circuit being connected between said control

- means and the junction of said second coil with said composite impedance; and a connection between said cathode and the junction of said composite impedance with said tuning condenser; said electrical circuit being so proportioned and arranged as to produce a controlled, progressive, retroactive unbalance thereof of a type which increases with increasing wavelength at a pre-determined rate over a given range of frequencies.
4. An electrical amplifier circuit comprising, in combination, a vacuum tube having at least an anode, a cathode, and a control element; an input circuit associated with said control element and cathode; an output circuit including a coil connected between said anode and cathode, a second coil coupled thereto in the reverse sense, a composite impedance connected in series with said second coil and including a third coil having negligible electromagnetic coupling with said second coil and a capacity, and a tuning condenser connected across said second coil and said composite impedance in series to form a tuned circuit; and a capacitive impedance arranged between said control element and a point in said tuned circuit; said electrical amplifier circuit being so proportioned and arranged as to produce a controlled, progressive, retroactive unbalance thereof of a type which increases at a predetermined rate as the tuned circuit is adjusted to resonance at frequencies further removed from the predetermined frequency at which the reactive balance of the circuit is substantially perfect.
5. An electrical amplifier circuit comprising, in combination, a vacuum tube provided with anode, cathode and control electrodes, an output transformer having its primary associated with said anode and cathode elements and its secondary effectively reversed as regards its primary, a composite impedance connected to said secondary and including a balance coil having negligible electromagnetic coupling with said primary and secondary and an unbalancing capacity, a tuning condenser connected across said secondary and composite impedance in series, and a balance capacity connected between said composite impedance and said grid electrode, said unbalancing and said balance capacity being so proportioned that the circuit is non-oscillatory throughout the frequency range of said amplifier circuit when adjusted for reactive balance at the higher end of the frequency range.

In testimony whereof, I affix my signature.
LEWIS M. HULL.
